UNITED STATES PATENT OFFICE.

MARIE DIXON, OF NEUTRAL BAY, NEAR SYDNEY, NEW SOUTH WALES, AUSTRALIA.

SELF-COOLING SAFE FOR VIANDS.

1,381,064.

Specification of Letters Patent.

Patented June 7, 1921.

Application filed February 18, 1920. Serial No. 359,612.

To all whom it may concern:

Be it known that I, MARIE DIXON, subject of the King of Great Britain and Ireland, residing at "Remuera," 47 Kurraba road, Neutral Bay, near Sydney, New South Wales, Australia, have invented certain new and useful Improvements in Self-Cooling Safes for Viands, of which the following is a specification.

10 This invention relates to self cooling safes for containing meat and other viands in domestic service. It consists in certain improvements in that type of such safes in which heat is absorbed in evaporation of 15 water into the surrounding atmosphere from the surfaces of porous material of which the walls of the safe are constructed.

Self cooling safes according to my invention are constructed of elements of cellular 20 Portland cement concrete having the cells charged with porous coke or like neutral vesicular material, and structurally formed to interlock when completely assembled, thereby to enable easy erection and dis- 25 assembling, with means for facilitating the supply of water to the porous surfaces from which evaporation takes place, and for preventing access of ants to the safe chamber.

In the accompanying drawing, Figure 1 30 is an horizontal section through the safe and Fig. 2 is a vertical section on the plane 2—2 Fig. 1.

The base slab 10 is made of solid Portland 35 cement concrete, with feet 11. Its rim or marginal portion which sets out beyond the side walls and door line is formed as a continuous trough 12 to contain water which serves the double purpose of maintaining the slabs in wet condition and forming a 40 barrier which ants will not pass to reach the contents of the safe. A groove 13 and a spigot rib 14 on the top face of the slab 10 along three sides of the same form a footing complementary to the grooved section 45 of the bottom ends of the side and back slabs to engage said side and back slabs in correct erect position on the base slab 10.

The back slab 15 is formed with splayed ends which when set into the rabbets in the rear 50 ends of the side slabs 16 make a joint close enough to prevent substantial leakage of heat or intrusion of insects, but not necessarily air tight. The back slab 15 and the side slabs 16 depend for their positioning 55 at their bottom ends on the groove and

spigot seating 13—14 already described; near the top they are connected together by cabin hooks 17, the shank and eye tangs of which are respectively inserted in the concrete during the molding operation. Four 60 or more metal lugs 19 similarly fixed in the side slabs in the molding operation are provided for supporting a shelf or pan 20 of sheet metal or fiber board.

The back slab 15 and the side slabs 16 are 65 similarly constructed. The lower part 21 and the upper part 22 of each of them is of solid concrete, and the middle part 23 is a cavity wall with wire netting reinforcement 24 set in the solid portions of the structure 70 at either side of the cavity in the molding operation. The cavities 25 are packed with porous coke or "breeze" or pumice. 26 are ventilation holes through the upper solid portions 22 of each slab. The front ends of 75 the side slabs 16 are returned laterally inward as shown at 27 and 28, and finished to form splayed jamb rabbets for the door 29, the door being complementarily rabbeted to make a reasonably close draft proof 80 joint with said jamb rabbets. The door 29 is hung on hinges 30, the leaf tangs of which are embedded in the concrete of the door jamb, and in one outer corner of the door. 31 is a snap latch fastening device, of any 85 well known type, sufficing to hold the door closed home. 32 is a metal handpiece fixed in the door face.

Two water inflow vents screened with finely perforated gratings 33 are formed in 90 the upper part of the back slab 15 and two similar grated vents are formed in the upper part of each of the two side slabs 16 to offer passageway for water into the cavities 25. Grooves 34 are formed in the top edges of 95 the back and side slabs to spigot joint the cover 35 onto them and so hold the whole structure rigid when assembled. These grooves 34 terminate near the door jambs 36 and 37.

The cover 35 is formed with a central water reservoir cavity 38 open at the top, where a funnel mouth 39 is formed, a grating or gauze 40 being set in this funnel mouth to protect the contents of the cavity 105 38 and to prevent introduction of solid matter into it. The cavity 38 is packed with a lower layer 41 of sand and an upper layer 42 of coke, breeze, or pumice pieces. 43 are fine drip holes positioned to locate directly 110

over the gratings 33. 44 are lug ribs or spigots which fit into the grooves 34 for the purpose hereinbefore explained.

5 The joints at the slab junctions are not luted or otherwise closed. The safe may therefore be "knocked down" for packing or transport or when out of use.

10 Water is filled into the cavity 38 and into the trough 12 and is from time to time replenished. It is absorbed into the concrete mass of the slabs, and evaporation losses are made good by further absorption from the reservoir cavity 38 from which water percolates and trickles through the drip holes 43. 15 The packing in the cellular spaces holds a considerable quantity of water which from them reaches the slab surfaces which are exposed to atmosphere. In the evaporation of water from those surfaces into the surrounding atmosphere, heat is absorbed from the mass of the safe, and the temperature within it is thus maintained at a sufficiently low point to insure satisfactory keeping of meat and other viands stored in the safe.

20 25 More particularly in cool weather the side and back slabs may become overcharged with water. Any drip consequent on such overcharge of water will be collected in the trough 12 thus replenishing it. The base slab 10 and the underneath portion of the cover 35 should be constructed of dense concrete in order to minimize water percolation through them. The top side of the

20 cover 35, and the back slab and the side slabs and also the door are preferably constructed 35 of porous concrete.

The door is formed with a cavity 45, which, like the other slab cavities, is loosely packed with a water absorbent substance. The door may be splashed with water from time to 40 time to keep it in wet condition, but ordinarily it will absorb sufficient moisture from the slabs with which it is in contact to maintain it in a permanently damp condition.

What I claim as my invention and desire 45 to secure by Letters Patent is:—

1. A viand safe constructed of knockdown slabs of concrete with interfitting joints, having cellular cavities packed with absorbent material in the lateral slabs, a marginal 50 water gutter in the bottom slab, and a top vented water reservoir chamber packed with porous material in the cover slab.

2. A viand safe as defined in claim 1, having vents in the top of the lateral slab cavities and drip holes in the cover slab registering with said cavity vents and adapted to pass water from a water reservoir in the cover slab into said lateral slab cavities. 55

In testimony whereof I affix my signature 60 in the presence of two witnesses.

MARIE DIXON.
